UNITED STATES PATENT OFFICE.

PERCY COX AND FRANK McPARTLAND, OF JOHNSON CITY, NEW YORK, ASSIGNEES TO
ENDICOTT JOHNSON CORPORATION, OF ENDICOTT, NEW YORK, A CORPORATION OF
NEW YORK.

SHOE.

Application filed August 26, 1927. Serial No. 215,738.

This invention is a novel improvement in shoes and method of making same, and the principal object of the invention is to provide a shoe having a novel continuous rubber caulk welt fastened to the inturned upper around the entire margin and the sole and heel portion thereof and interposed between the upper and outer sole, which sole may be either McKay stitched or nail fastened to the inner sole through said caulk welt and inturned portion of the upper.

Another object of the invention is to provide a novel method for making shoes in which a rubber caulk welt is stapled to the upper inturned around the entire margin of the sole and heel portions thereof while the upper is still on the last, and before the sole is applied.

The use of our novel upper caulk welt extending around the entire margin of the sole and heel portions of the upper renders the shoe sole more nearly waterproof than would a welt which extends only part way around. When the caulk welt extends merely from the breast of the heel at one side around the sole to the breast of the heel, at the other side, there are slight openings left on both sides of the shoe sole at the places where the welt ends, and through these openings water may enter the shoe. Our continuous welting however overcomes this difficulty. Our caulk welt is fastened to the upper by means of staples before the last is pulled from the shoe, and the sole is then nail fastened or McKay sewed. The use of a continuous caulk welting extending entirely around a nail bottom shoe makes a stronger fastening between the sole and upper than stitching, thereby making such shoe more nearly waterproof than caulk welts on stitchdowns or Goodyear welt shoes.

We will explain the invention with reference to the accompanying drawing which illustrates one practical embodiment thereof to enable others familiar with the art to adopt and use the same; and will summarize in the claims the essential features of the invention, the novel features of construction, and novel combinations of parts, for which protection is desired.

In said drawings:

Fig. 1 is a bottom plan view of a shoe showing the edges of the upper turned in over the inner sole which is secured to the

last, and our novel continuous caulk welt 55 stapled around the entire margin of the sole and heel portions of the inturned upper.

Fig. 2 is a section in the line 2—2, Fig. 1;

Fig. 3 is a section through the completed shoe.

As shown in Figs. 1 and 2, the last A is placed in the upper 1, and an inner sole 2 is tacked as at 2^a to the bottom of the last. The outer edges of the upper 1 and lining 3 are turned inwardly as at 1^a, 3^a, over the 65 edge of the inner sole 2, and are secured to the inner sole and last by a row of tacks 4 or the like passing through the upper 1^a, lining 3^a, inner sole 2, and into last A.

While the last A is still in the shoe upper, 70 our continuous caulk welt 5 is applied, said welt 5 extending around the entire margin of the sole and heel portions of the inturned upper as shown in Fig. 1, and secured by a 75 row of staples 5^a passing through the welt 5, upper 1^a, lining 3^a, inner sole 2 and into the last A. Welt 5 may be formed of rubber, composition material, or leather, but preferably welt 5 is formed of soft rubber having an inseparable fabric backing, the 80 outer edge of the welt having a thickened portion 5^b and the inner edge thereof feathered as at 5^c. The welt consists of strip 5 affixed to the inturned upper 1^a, which in practice begins near the heel at the inside, 85 and is fastened on with staples 5^a as the edge of the shoe is held against the guide roller of the stapling machine, and after the welt has been extended thus entirely around the sole and heel portions of the inturned upper the welt is cut off so that the two ends butt together on a slight bevel so as to slightly overlap, and a staple is driven in at the point where the ends meet and overlap.

A filler 6 may be applied in the usual manner, and an outer sole 7 applied preferably by nails 7^a passing through sole 7, welt 5, upper 1^a, lining 3^a, inner sole 2, as shown in Fig. 3. If desired the sole 7 may be McKay sewed to the inner sole 2, the stitches passing 90 through the welt and upper.

The continuous caulk welt extends around the entire margin of the sole and heel portions. This we consider an important feature for the reason that it makes the shoe more nearly waterproof than would a welt which passes only part way around, for slight openings would be kept on both sides

of the shoe where the welt ends through which water might enter the shoe. Our continuous welting overcomes this difficulty.

Our continuous caulk welt is fastened to the upper by means of staples before the last is pulled from the shoe. The sole is then nailed on or McKay sewed. The use of a continuous caulk welting extending entirely around a nail bottom shoe is superior to the weltings in stitchdowns and Goodyear welts heretofore used for the reason that nails make a stronger fastening between the sole and the upper than does stitching, thereby making the shoe more nearly water-proof than caulk welts on stitchdowns or Goodyear welt shoes.

We do not limit our invention to the exact form shown in the drawing, for obviously changes may be made therein within the scope of the claims.

We claim:—

1. In a McKay shoe, a continuous caulk welt stapled to the inner sole through the upper and extending around the sole and heel portions between the outer sole and upper.

2. In a McKay shoe, a continuous rubber caulk welt stapled to the inner sole through the upper and extending around the margin of the sole and heel portions thereof and interposed between the outer sole and upper.

3. In a shoe having an inner sole and in-turned upper; a continuous caulk welt extending around the margin of the sole and heel portions of the in-turned upper; fastenings through the welt, upper, and inner sole; an outer sole; and means connecting the outer and inner soles through the welt and upper.

4. In a shoe having an inner sole and in-turned upper; a continuous caulk welt extending around the sole and heel portions of the in-turned upper; staples connecting the welt to the inner sole through the upper; an outer sole; and means connecting the outer sole to the inner sole through the welt and in-turned upper.

5. In a shoe, an inner sole; an upper whose edges are turned in over the inner sole; means connecting the in-turned upper to the inner sole; a continuous caulk welt extending around the margin of the sole

and heel portions of the in-turned upper; staples connecting the welt to the inner sole through the upper; an outer sole; and means connecting the outer and inner soles through the welt and upper.

6. A shoe comprising an upper; an inner sole, the edges of the upper being turned in over the inner sole; tacks connecting the in-turned upper to the inner sole; a continuous caulk welt extending around the margin of the sole and heel portions of the upper; staples connecting the welt and inner sole through the upper; a filler; an outer sole; and nails connecting the outer and inner soles through the welt and upper.

7. The method of making shoes, consisting in placing the last in the upper; fastening an inner sole to the last; turning in the edges of the upper over upon the inner sole; fastening the in-turned upper to the inner sole; placing a continuous caulk welt around the margin of the in-turned upper; fastening the welt to the inner sole through the upper; and securing an outer sole by fastenings passing through the welt and inner sole.

8. The method of making shoes, consisting in placing the last in the upper; fastening an inner sole to the last; turning in the edges of the upper over upon the inner sole; fastening the in-turned upper to the inner sole; placing a continuous caulk welt around the margin of the in-turned upper; stapling the welt to the inner sole through the upper; and securing an outer sole by fastenings passing through the welt and inner sole.

9. The method of making shoes consisting in placing the last in the upper; fastening an inner sole to the last; turning in the edges of the upper over upon the inner sole, fastening the in-turned upper to the inner sole; placing a continuous caulk welt around the margin of the in-turned upper; stapling the welt to the inner sole through the upper; applying a sole filler; laying the outer sole; removing the last; and securing the outer sole by nails passing through the welt, upper, and inner sole.

In testimony that we claim the foregoing as our own, we affix our signatures.

PERCY COX.
FRANK McPARTLAND.
